ERIK AUGUST FORSBERG, OF FLEMINGGATEN-STOCKHOLM, SWEDEN, ASSIGNOR TO
AKTIEBOLAGET SEPARATOR, OF STOCKHOLM, SWEDEN, A COMPANY.

CENTRIFUGAL CREAM-SEPARATOR.

964,505.

Specification of Letters Patent. Patented July 19, 1910.

Application filed June 12, 1909. Serial No. 501,688.

To all whom it may concern:

Be it known that I, ERIK AUGUST FORSBERG, a subject of the King of Sweden, and residing at Fleminggaten 8, Stockholm, Sweden, chief engineer, have invented certain new and useful Improvements in Centrifugal Cream-Separators; and I do hereby declare the following to be a full, clear, and exact description of the invention, such as will enable others skilled in the art to which it appertains to make and use the same, reference being had to the accompanying drawings, and to letters of reference marked thereon, which form a part of this specification.

My invention relates to an improvement in the covers surrounding the rotating bowl of centrifugal cream separators for collecting and discharging the separated liquids.

In most centrifugal cream separators the rotating bowl is surrounded by a still standing vessel on the top of which are superposed two covers provided with central openings for the bowl neck from which the separated fluids are thrown out in the chambers formed by the said covers and from which the liquids are further discharged. By this arrangement of the receivers for the separated liquids the disadvantage occurs that the froth arising from the quick out-rush of the liquids as well as the vapors occurring when the separation takes place at a relatively high temperature, under certain circumstances flow from the covers or receivers to the vessel surrounding the rotating bowl. Apart from the disadvantages resulting herefrom as milk-splash and uncleanliness, the penetrating of the liquid into the separator frame causes frequently serious consequences depending thereupon that the bowl as well as the driving mechanism of the separator become rusty. The reason why the liquids and vapors are penetrating to the frame is that the separator bowl during its rotation, on account of the friction imparts a rotative movement to the air which is arrested in the surrounding vessel and thus works like a ventilating fan. Thereby an air-current occurs, which according to the circumstances either will be directed from the covers to the vessel or from the same to the covers. In the last mentioned case this air-current causes no disadvantage at

all, but is, on the contrary, favorable, because it assists in driving out from the covers the liquids thrown out from the bowl. In the former case again the air-current causes the sucking in of vapors and froth from the covers into the vessel, whereby the said disadvantages occur.

My invention relates to an improvement, by means of which the air is always caused to flow in the direction from the vessel to the covers, whereby the entering of froth and vapors into the vessel is prevented. This object I have effected by the means which are hereinafter described and claimed, and which are illustrated in the accompanying drawing, in which—

—A— is the separator-bowl, —B— the vessel surrounding the same and —C— the skimmilk cover. Between the bowl —A— and this cover a number of radial wings —D— are arranged. When the bowl rotates, the air arrested in the vessel is also brought in a rotating movement, whereby, on account of centrifugal force, the pressure is gradually increased toward the periphery of the vessel. On account of the wings the air resting near the skim-milk covers is, however, prevented from taking part in the rotating movement, and as centrifugal force thus does not act at this place, the air flows under the influence of the excess of pressure prevailing at the periphery of the vessel —B— toward the center and upward through the central opening in the skim-milk-cover. In this manner a permanent air-current is thus effected in the direction from the vessel to the cover, whereby, as mentioned, the entering of froth and vapors into the vessel is prevented.

Claims.

1. In a centrifugal cream separator having a stillstanding vessel surrounding the rotating bowl and superposed covers for collecting the separated fluids thrown out from the bowl the combination of wings in the passage between the bowl and the proximate cover, said wings directing the air pressed in between them to the central opening of the cover.

2. In a centrifugal cream separator having a stillstanding vessel surrounding the rotating bowl and superposed covers for

collecting the separated fluids thrown out from the bowl the combination of radial wings in the passage between the bowl and the proximate cover, said wings directing the air pressed in between them to the central opening of the cover.

In testimony, that I claim the foregoing

as my invention, I have signed my name in presence of two subscribing witnesses.

ERIK AUGUST FORSBERG.
